Des. 213,987
Patented Apr. 29, 1969

213,987

KITE FLIGHT CONTROL HANDLE

Theodore A. Benze, 111 Western Concourse,
Amityville, N.Y. 11701

Filed July 30, 1968, Ser. No. 12,956

Term of patent 14 years

Int. Cl. D21—04, 99

U.S. Cl. D34—15

FIG. 5

FIG. 1 is a front elevational view of a kite flight control handle, showing my new design;

FIG. 2 is a bottom end view of FIG. 1, looking in the direction of the arrows 2-2;

FIG. 3 is a rear elevational view thereof;

FIG. 4 is a top end view of FIG. 1; and

FIG. 5 is a section taken on line 5-5 of FIG. 1.

I claim:

The ornamental design for a kite flight control handle, as shown.
